HUSKING DEVICE

Wilbur J. Coulter, Moline, Ill., assignor to Deere & Company, Moline, Ill., a corporation of Illinois

Application September 14, 1936, Serial No. 100,639

9 Claims. (Cl. 130—5)

This invention relates to corn husking mechanisms of the type comprising a plurality of husking rolls equipped with husking pegs, and the object thereof is to provide a new husking peg and means for securing it in position in a husking roll.

It is a common practice to provide in husking rolls husking pegs in the form of relatively flat projections, such as disclosed in Patent 1,970,797, issued to me on August 21, 1934, or in the form of pins of circular cross-section, and to fix these in position in the husking roll by inserting wooden plugs in radially extending holes in the husking roll, and then driving the pegs into the plugs.

Driving a peg of either of these shapes into a wooden plug splits the plug into two parts, causing the two parts of the plug to act as wedges to hold the peg in position. I have found that in practice, while the peg when mounted as described above is fairly well held against movement in the direction perpendicular to the plane of the split of the plug, it is not securely held against movement in the direction in line with the split of the plug. As a result of not being held securely against movement in both directions, the plug on occasion after hard usage drops out.

I have also found that in order to obtain sufficient strength in the pegs to withstand hard usage, without resorting to special treatment of the metal, it is necessary to make the pegs of rather heavy stock. When a peg of heavy stock is driven into a wooden plug, too much of the stock of the plug is ruptured to obtain a good wedging action on the peg by the remaining parts of the plug.

Specifically, the object of my invention is to provide a peg of a particular shape such that the required strength will be obtained without resorting to heavy stock material, and such that when the peg is driven into position, the plug will be split into three parts instead of only two, which will provide wedging forces against the plug at 120 degree angles, so that the peg will be held against movement in all directions and will thereby be securely wedged and locked in position. To accomplish this, I provide a peg which is angular in cross-section, the material itself being relatively thin. The angular cross-section causes the wooden peg to be split into three parts. By disposing the peg so that the edge at the line of intersection of the two faces thereof is the leading edge with reference to the direction of rotation of the roll and with the faces of the peg making substantially equal angles with a plane perpendicular to the axis of the roll, the strength of the peg to resist the stresses imposed upon it is greatly increased over that of prior pegs, and by flattening the end of the peg into a plane perpendicular to the leading edge, a relatively sharp point is provided at the outer end of the edge, which gives the peg exceptionally good husking characteristics.

A preferred embodiment of my invention is described in the following specification and disclosed in the accompanying drawing in which:

Fig. 1 is a fragmentary top view of the delivery end of two rolls of a corn husking mechanism, one of which is equipped with my new husking pegs;

Fig. 2 is an enlarged top view of one of the pegs mounted in position;

Fig. 3 is a cross-sectional view along the line 3—3 of Fig. 2, and

Fig. 4 is an enlarged perspective view of one of the pegs.

Husking rolls 11 and 12, which are mounted in close proximity to each other, and are rotated in opposite directions at the same speed, are equipped with toothed spirals 13, which function to remove the husks from the ears of corn guided down over the top of the rolls. The roll 11 is equipped with husking pegs 14 to tear free those husks not so readily removable. A recess 15 is provided in roll 12 to receive pegs 14.

My new design of husking peg is best shown in Fig. 4. It is angular in cross-section, comprising two flanges 15 and 16, disposed at an angle of 90 degrees to each other. The outer end 17 of the peg is ground flat, the plane thereof being perpendicular to the edge 18 at the line of intersection of the two outer faces of the flanges 15 and 16. As a result, a sharp point 19 is formed at the juncture of this edge with the end of the peg. The inner portions of the flanges 15 and 16 have been narrowed to provide the shoulders 21 and 22, and these narrowed portions have been tapered towards the inner end of the peg to better adapt it for mounting it in

The peg 14 is mounted in position in the roll by inserting a wooden plug 25 in a radially extending hole 26 in the wall 27 of the husking roll, and then driving the peg into the wooden plug until shoulders 21 and 22 contact the end 18 of the plug. The peg is positioned with the edge 18 leading with reference to the direction of rotation of the roll, and with the two faces of the flanges 15 and 16 making equal angles with a plane perpendicular to the axis of the roll. In

- the operation of driving the peg into the wooden plug, the wooden plug is split, in this instance into three parts 28, 29, and 30, as best shown in Fig. 2. The three parts exert wedging forces against said peg at approximately 120 degree angles. As a result, the peg 14 is securely held against movement in all directions. Preferably, the wooden plug 25 is made longer than the thickness of the wall of the husking roll, and when the peg is driven into the plug, the portion of the plug extending inwardly of the inner margin of the hole in the husking roll wall, spreads outwardly as shown in Fig. 3. These outwardly spread portions of the wooden plug parts also aid in holding the peg in position and prevent the plug and peg from coming out.

What I claim is:

1. The combination with a husking roll having a radially extending hole in its periphery and adapted for rotation in one direction, of a wooden plug disposed in said hole, and a husking peg driven into said plug, said peg being angular in cross-section and positioned to dispose the edge at the line of intersection of the two faces thereof radially with respect to the axis of said roll with the faces making equal angles with a plane perpendicular to the axis of said roll and with said edge leading with reference to the direction of rotation of said roll.
2. The combination with a husking roll having a radially extending hole in its periphery and adapted for rotation in one direction, of a wooden plug disposed in said hole, and a husking peg driven into said plug, said peg being angular in cross-section and positioned to dispose the edge at the line of intersection of the two faces thereof radially with respect to the axis of said roll with the faces making equal angles with a plane perpendicular to the axis of said roll and with said edge leading with reference to the direction of rotation of said roll.
3. The combination with a husking roll having a radially extending hole in its periphery and adapted for rotation in one direction, of a wooden plug disposed in said hole, and a husking peg driven into said plug, said peg being angular in cross-section, said plug being split into three parts by the driving of said peg into said plug, said three parts exerting a wedging force against said peg to securely wedge said peg in position.
4. The combination with a husking roll having a radially extending hole in its periphery and adapted for rotation in one direction, of a wooden plug disposed in said hole, and a husking peg driven into said plug, said peg being angular in cross-section, said plug being split into three parts by the driving of said peg into said plug, said three parts exerting wedging forces against said

peg at 120 degree angles to securely wedge said peg in position.

5. The combination with a husking roll comprising a hollow tube and having a hole extending radially through the wall thereof and adapted for rotation in one direction, of a wooden plug disposed in said opening, the inner end projecting beyond the inner margin of said opening, and a husking peg driven into said plug, said peg being angular in cross-section and positioned to dispose the edge at the line of intersection of the two faces thereof axially with respect to said hole and the leading edge with reference to the direction of rotation of said roll and with the faces of said peg making equal angles with a plane perpendicular to the axis of said roll, said plug being split into three parts by the driving of said peg into said plug, the three parts exerting wedging forces against said peg at 120 degree angles and the inwardly projecting end portions being spread beyond the margin of the hole to securely wedge and lock said peg in position.

6. The combination with a husking roll having a radially extending hole in its periphery and adapted for rotation in one direction, of a wooden plug disposed in said hole, and a husking peg driven into said plug, said peg being angular in cross-section and positioned to dispose the edge at the line of intersection of the two faces thereof radially with respect to the axis of said roll with the faces making equal angles with a plane perpendicular to the axis of said roll and with said edge leading with reference to the direction of rotation of said roll, the outer end of said peg lying in a plane perpendicular to said edge to form a relatively sharp point at the outer end of said edge.

7. In combination with a cylindrical husking roll, a husking peg of V-shaped cross section, comprising a pair of flange portions intersecting in a line extending longitudinally of said peg, and means for securing said peg to said roll in a position with said line of intersection extending substantially radially with respect to said roll.

8. In combination with a rotatable husking roll, a husking peg of V-shaped cross section, comprising a pair of converging flanges, and means for securing said peg to said roll in a position in which said flanges converge in the direction of movement of said peg as the roll rotates.

9. In combination with a husking roll, a husking peg having a pair of flange portions providing a pair of surfaces intersecting in a line extending longitudinally of said peg, said peg terminating at one end in a plane intersecting said surfaces to provide a sharp point for engaging ears of corn during husking operation, the other end of said peg having a tapered shank portion adapted to be driven into a plug supported in said roll.

WILBUR J. COULTAS.
